US00D888723S

(12) **United States Design Patent** (10) Patent No.: **US D888,723 S**
(45) Date of Patent: ** Jun. 30, 2020

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Wonheui Jung**, Seoul (KR); **Sunkyoung Kim**, Seoul (KR); **Hyemi Lee**, Seoul (KR)

(73) Assignee: **Samsung Electronics Co., Ltd.**, Suwon-si (KR)

(**) Term: **15 Years**

(21) Appl. No.: **29/615,992**

(22) Filed: **Sep. 1, 2017**

(30) **Foreign Application Priority Data**

Mar. 27, 2017 (KR) 30-2017-0013986

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The broken lines in the FIGURE depict a display screen or portion thereof and form no part of the claimed design.

1 Claim, 1 Drawing Sheet
